Patented Aug. 3, 1920.

UNITED STATES PATENT OFFICE.

CARL F. BRANDENBERGER, OF FORT MADISON, IOWA.

SPRING TENSION FOR POWER OR HAND PUMPS.

1,348,203.

Specification of Letters Patent.

Patented Aug. 3, 1920.

Application filed February 12, 1919. Serial No. 276,541.

To all whom it may concern:

Be it known that I, CARL F. BRANDENBERGER, a citizen of the United States, residing at Fort Madison, in the county of Lee and State of Iowa, have invented a new and useful Spring Tension for Power or Hand Pumps, of which the following is a specification.

It is the object of this invention to provide novel means whereby strains on a pump rod will be avoided.

When a windmill is operated at a high speed the water is frequently forced into the supply pipe faster than it can escape therefrom and one object of the invention is to provide a spring tension device which will act as a governor, in that the stroke will shorten, as the speed and as the load increase.

Within the scope of what is claimed, a mechanic can make changes, without departing from the spirit of the invention.

In the drawings:—

Figure 1 shows in longitudinal section, a device constructed in accordance with the invention; Fig. 2 is a cross section on the line 2—2 of Fig. 1; Fig. 3 is a cross section on the line 3—3 of Fig. 1; Fig. 4 is a cross section on the line 4—4 of Fig. 1; and Fig. 5 is an elevation showing a modification, parts being broken away.

The invention comprises a tubular casing 1, bifurcated at its upper end to form arms 2 which are trough-shaped in cross section. The lower end of one part 3 of a pump rod is received between the arms 2 and is held therebetween by bolts 40 or the like. A cap 5 is threaded on the lower end of the casing 1, a plunger 6 being mounted to reciprocate in the cap and being provided at its upper end with a head 7. A compression spring 8 surrounds a portion of the plunger 6, within the casing 1, one end of the spring abutting against the head 7, and the other end of the spring abutting against the cap 5. A socket 9 is threaded on the lower end of the plunger 6 and limits the upward movement of the plunger under the action of the spring 8, the socket having arms 10 terminating in a ring 11 in which is received another part 12 of the

pump rod. A pin 14 is inserted through the part 12 of the pump rod and through the ring 11 and is provided at one end with an eye 15. The other end of the pin is supplied with ears 18 between which is received, a thinned projection 17 on one end of a tongue 16, a pivot element 19 passing through the part 17 and through the ears, the tongue being bluntly pointed at its lower end, as shown at 20, to facilitate the insertion of the tongue through the projection 17 and the ears 18. When the pin 14 is in place, the tongue 16 will swing into a depending position and hold the end 14 in place against withdrawal. On the upstroke, the spring 8 will be compressed, and on the down stroke, the spring will expand, the plunger 6 sliding in the cap 5 during the operation above mentioned. The construction, obviously, is such that sudden strains on the pump rod will be avoided. The device is adapted to be used on a pump rod of any kind, whether the pump be operated by a wind mill, by a hand lever or otherwise.

In case it should be necessary to mount the device relatively close to the pump, at which location, a rod of circular cross section is likely to be encountered, then recourse is had to the structure shown in Fig. 5, wherein parts hereinbefore described have been designated by numerals previously used, with the suffix "a." In Fig. 5, a collar 21 is threaded on the upper end of the casing 1^a and carries a reducer 22 receiving one part 23 of the pump rod. A socket 9^a is threaded on the lower end of the plunger 6^a and receives the lower part 25 of the pump rod.

Having thus described the invention, what is claimed is:—

In a device of the class described, a cylindrical casing; a cap threaded on one end of the casing; a plunger slidable in the cap and provided at its inner end with a head located in the casing; a socket threaded on the outer end of the plunger and having spaced lower arms; a compression spring surrounding the plunger within the casing and abutting at its ends against the cap and the head, the spring serving to hold the socket normally in engagement with the

cap, the upper end of the casing being enlarged and tapered to facilitate the insertion of the plunger and the head into the casing and being bifurcated to form upper arms which are trough-shaped in cross section; a connecting element uniting the upper arms; and a connecting element uniting the lower arms.

In testimony that I claim the foregoing as my own, I have hereto affixed my signature in the presence of two witnesses.

CARL F. BRANDENBERGER.
